UNITED STATES PATENT OFFICE

2,323,941

CENTRIFUGAL COMPRESSOR

Chester W. Smith, Lynn, Mass., assignor to General Electric Company, a corporation of New York

Application February 14, 1942, Serial No. 430,941

6 Claims. (Cl. 230—114)

The present invention relates to centrifugal compressors comprising a rotating impeller which receives fluid to be compressed at a central portion or eye and discharges it to a diffuser which functions to convert the velocity of the fluid into pressure, the fluid passing from the diffuser to a discharge scroll. The diffuser comprises a plurality of circumferentially spaced curved vanes which define diffuser passages through which the fluid being pumped flows and which passages are shaped to convert velocity into pressure.

It is known that to obtain best efficiency at various loads on a centrifugal compressor, the discharge vanes should be adjustable so that the shape of the diffuser passages can be varied in accordance with the load. The object of my invention is to provide an improved construction and arrangement for accomplishing this result.

For a consideration of what I believe to be novel and my invention, attention is directed to the following specification and the claims appended thereto.

In the drawing, Fig. 1 is a front view, partly in section, of a centrifugal compressor embodying my invention, and Fig. 2 is a detailed sectional view taken on line 2—2 of Fig. 1.

Referring to the drawing, 1 indicates the casing of a centrifugal compressor, 2 the shaft which is mounted in suitable bearings (not shown), 3 the impeller carried by shaft 2, and 4 the diffuser vanes. The diffuser vanes surround the impeller and are suitably supported on a diffuser plate or wall 5. Fluid to be compressed, air for example, is supplied to the impeller at its central portion through an opening 6 in the casing and is discharged at the periphery of the impeller to the diffuser passages formed by vanes 4. From the diffuser passages, the fluid flows to the discharge scroll 7 and out through discharge outlet 8.

According to my invention, I make the diffuser vanes 4 hollow and construct the inner ends of the vanes in the form of curved flexible tips 9 which are unattached to the side walls of the diffuser. I then connect the space within the vanes with a region of higher pressure in the diffuser whereby the flexible tips are subjected to such pressure and are positioned thereby, the pressure in the tips tending to straighten them after the manner of a Bourdon tube. In the present instance, the spaces within the diffuser vanes are open at their outer ends as is indicated at 10 so that the tips 9 are subjected to the pressure in this region, which is the region of

highest pressure, being at the discharge end of the diffuser passages.

The vanes may be attached to plate or wall 5 of the diffuser in any suitable way, as by welding, casting or brazing, and the free ends 9 may be of a length to give the desired amount of adjustment. Plate 5 is suitably attached to one side wall of the compressor casing by any suitable means. The passages between the vanes are closed on the side opposite plate 5 by the adjacent casing wall.

In the operation of a centrifugal compressor, the pressure increases as the flow decreases so that as the flow decreases, the flexible ends 9 tend to straighten, thus moving closer to the surfaces of the adjacent vanes whereby the diffuser inlet area is lessened. This is set forth in Fig. 1 wherein the vanes are shown in one position in full lines and in an adjusted position in dotted lines. Thus, by my invention the diffuser inlet area is automatically decreased as the load decreases and is increased as the load increases. The lengths of the free ends 9 and their flexibility are so arranged that with the pressures available the desired amount of flexing or movement will take place.

In accordance with the provisions of the patent statutes, I have described the principle of operation of my invention, together with the apparatus 30 which I now consider to represent the best embodiment thereof, but I desire to have it understood that the apparatus shown is only illustrative and that the invention may be carried out by other means.

What I claim as new and desire to secure by Letters Patent of the United States, is:

1. A centrifugal compressor having spaced flexible diffuser vanes which define passages for the flow of fluid and which are subjected to and adjusted relatively to each other by pressure set up by the compressor to vary the contour of the discharge passages between the vanes.

2. A centrifugal compressor having diffuser vanes which define passages for the flow of fluid, 45 said vanes being provided with flexible tips, and means for subjecting said tips to pressure set up by the compressor for adjusting said tips to vary the contour of the discharge passages between the vanes.

3. A centrifugal compressor having diffuser vanes which define passages for the flow of fluid, said vanes being provided with curved hollow flexible tips, and means whereby the interior of the tips are subjected to pressure set up by the 55 compressor for adjusting said tips to vary the

contour of the discharge passages between the vanes.

4. A centrifugal compressor having curved hollow flexible diffuser vanes which define passages for the flow of fluid, and means whereby the interior of said vanes are subjected to pressure set up by the compressor to effect adjustment of the vanes relatively to each other to vary the contour of the discharge passages between the vanes.

5. A centrifugal compressor having a diffuser comprising a side plate and curved vanes attached thereto in spaced relation to each other to define diffuser passages, ends of vanes at the entrance side of the diffuser being flexible and

free to move toward and away from adjacent vanes, and means for subjecting said ends to pressure set up by the compressor for effecting movement of such tips.

6. A centrifugal compressor having a diffuser comprising a side plate and curved vanes attached thereto in spaced relation to each other to define diffuser passages, said vanes at their entrance ends being in the form of curved hollow

10 flexible parts free to move toward and away from adjacent vanes, and means for subjecting said hollow parts to pressure set up by the compressor for effecting adjustment of such flexible parts.
